[57] CLAIM

The ornamental design for a holder for baby bottle and accessories, as shown and described.

DESCRIPTION

FIG. 1 is a front perspective view of a holder for baby bottle and accessories, showing my new design;

FIG. 2 is a front elevation view;

FIG. 3 is a left side elevation view, the right side elevation view being a mirror image thereof; and,

FIG. 4 is a top plan view.

The undisclosed rear and bottom views are planar and unornamented.
